(57) **CLAIM**

The ornamental design for a light emitting diode (LED) pendent lamp, as shown and described.

DESCRIPTION

FIG. 1 is a front elevation view of a light emitting diode (LED) pendent lamp showing the new design;

FIG. 2 is a rear elevation view thereof;

FIG. 3 is a left side elevation view thereof, the right side being a mirror image;

FIG. 4 is a top plan view thereof;

FIG. 5 is a bottom plan view thereof;

FIG. 6 is a first perspective view thereof with peripheral members being in a first state;

FIG. 7 is a second perspective view thereof with peripheral members being in a second state; and,

FIG. 8 is a third perspective view thereof with peripheral members being in a third state.

The broken lines represent portions of the article that form no part of the claimed design.

1 Claim, 8 Drawing Sheets
